DESIGN FOR A PITCHER

Howard H. Boyce, Clarksburg, W. Va.

Application July 15, 1936, Serial No. 63,868

Term of patent 14 years

To all whom it may concern:

Be it known that I, Howard H. Boyce, a citizen of the United States, residing at Clarksburg, in the county of Harrison and State of West Virginia, have invented a new, original, and ornamental Design for a Pitcher, of which the following is a specification, reference being had to the accompanying drawing, forming part thereof.

Figure 1 is a top plan view of a pitcher showing my new design.

Figure 2 is a view in side elevation thereof.

Figure 3 is an elevational view, taken at right angles to Figure 2.

I claim:—

The ornamental design for a pitcher as shown.

HOWARD H. BOYCE.
